UNITED STATES PATENT OFFICE.

HYMAN ELI GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,727.

Specification of Letters Patent.

Patented July 21, 1908.

Application filed May 28, 1906. Serial No. 319,105.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

My invention relates to calculating machines including calculating typewriter attachments, and its object is to provide a safeguard against incorrect operation on the part of the operator. In printing numbers having three figures it is common to punctuate or "point off" by dividing the figures into groups of three and printing a comma or period between each group, or, what practically amounts to the same thing, to leave a space between each group, such space in typewriting being equal to a regular letter or figure space. In printing dollars and cents a period or space also occurs between the dimes column and the units dollars column. To illustrate, the most common practice is to write a number thus: \$4,382,967.22 or thus \$4 382 967 22. In either method when using the machines now in most general use there is a possibility that the operator may inadvertently omit the comma or space and print a figure there instead; or, if the machine is a non recording one, strike a key under such conditions that the value thereof would not be registered, or if registered would occur in the wrong ordinal or columnar place. As above indicated the object of this invention is to prevent such error on the part of the operator; and briefly stated, this object is accomplished by providing means for preventing the depression of the keys at the spacing or pointing-off points.

I accomplish my objects by the mechanism illustrated in the accompanying drawings in which:

Figure 1 is a general front elevation of a calculating typewriter attachment embodying the invention. Fig. 2 is a sectional elevation through the typewriter and totalizer, showing the interlocked connections between the keys and the receiving wheels. Fig. 3 is a front view of a totalizer embodying my invention, the cover or casing being removed to expose the operative parts. Fig. 4 is a sectional view through the figure wheels showing the manner of grouping or spacing the same. The section is taken, for example, on the line 4-4 Fig. 6. Fig. 5 is a sec-

tional elevation taken transversely through the totalizer. Fig. 6 is similar to Fig. 5, except that a different mechanism is shown for preventing the rotation of the master-wheel at the pointing-off point.

The totalizer here shown is in many respects identical with the totalizer shown and described in U. S. Patent No. 741,961 issued to me October 20, 1903, the main difference being in the grouping of the figure wheels and parts which actuate the same and in the adding of a locked piece at each of the pointing-off spaces in the totalizer. The mechanism which drives the totalizer and which is variously referred to in the art as the "differential", "valuating" or "digitizing" mechanism is substantially the same as the one shown and described in U. S. Patent No. 782,554 issued to me February 14, 1905. It is not essential that the invention be embodied in the totalizer and differential mechanism of the type here shown but it is applicable to other forms so long as the master-wheel and receiving wheels come into mesh ⁶⁵ ⁷⁰ ⁷⁵ ⁸⁰ ⁸⁵ ⁹⁰ ⁹⁵ ¹⁰⁰ ¹⁰⁵ ¹¹⁰ *seriatim* and the differential mechanism be geared in such manner that when in operative condition the master wheel is held from rotation and the keys cannot be depressed.

Referring first to the totalizer, the same consists of figure wheels 1, receiving wheels 2, carrying wheels 3, and carrying pinions 4. Wheels 1, 2 and 3 are independently rotatable on shafts 5, 6 and 7 respectively which are all supported in the totalizer casing 8. As explained in my prior totalizer patent above referred to each receiving wheel 2 meshes with a carrying wheel 3 and with a gear wheel 9 rigidly secured to or forming an integral part of its figure wheel for rotating it. The carrying pinions 4 engage the carrying wheels 3 in pairs and with them constitute a tens carrying mechanism.

The totalizer and the master wheel 10 have relative travel so that the receiving wheels shall be enmeshed *seriatim*, and in the present form of a typewriter attachment it is the totalizer which travels, it being mounted in this instance on a slide 11 which is made to travel lengthwise along stationary bar 12 by means of an arm 13 extending to said slide 105 from the typewriter carriage 14. Said carriage is supported on the typewriter framework 15 and travels thereon as a result of the depression of the typewriter keys 16 in the well known manner.

In the present totalizer the figure wheels, instead of being all equi-distant from each other are arranged in groups, three wheels to a group, with an intervening space between them equivalent to a letter or figure space. The single exception to this grouping is a group of two at the right end of the totalizer for dimes and cents. These spaces may be referred to as "pointing-off" spaces. There is a receiving wheel for each of the figure wheels in the totalizer and consequently said receiving wheels also occur in groups. Between each group of receiving wheels I place a non rotatable member which may vary greatly in its form but whose function is to prevent the master wheel from rotating when opposite to the pointing-off space in the totalizer. In Figs. 2 and 5 this non rotatable member is shown in the form of a piece 17 which is mounted upon shaft 6 and is provided with one or more teeth similar to the teeth of the receiving wheels 2. This piece is prevented from rotating by means of an arm 17^a which extends over the shaft 5, or other fixed piece in the totalizer and prevents the master wheel from rotating when the two are in juxtaposition. Other means may be employed for the purpose, for example the piece 17^b shown in Fig. 6. Said piece 17^b is practically identical with the receiving wheels but has a pin 18 extending through its hub 17^c and through the shaft 6. Said shaft in this form is non rotatable and consequently the pieces 17^b are non rotatable.

In the form of differential or digitizing or valuating mechanism which I have selected to illustrate this invention, the master wheel 10 is mounted upon a non traveling shaft 19 and is provided upon one side with the bevel gear 20 meshing with the pinion 21 on shaft 22. Said shaft is driven by means of the pinion 23 meshing with the bevel gear 24 formed upon the side of the spur gear 25. Said gear 25 is mounted upon the shaft 26 and is driven by means of a pinion 27 fixed on the digit shaft 28. Said digit shaft has rigidly fixed thereon a set of digit pinions adapted to be enmeshed by the teeth 29 formed upon the digit pieces 30 there being one of said digit pieces for each of the digits from 1 to 9. A digit gear wheel 31 is rigidly secured on the side of each digit piece for rotating it and there is a driving sector 32 adapted to mesh with each digit gear wheel 31. Said driving sectors are all independently rotatable upon the shaft 33 and are non yieldably connected to their respective figure keys 16 by means of the links 34. It is obvious from the above description that if the master wheel is prevented from rotating the keys cannot be depressed.

In operation, the depression of a key causes the step by step travel of the type-writer carriage and totalizer in the usual

manner and also causes the operation of the master wheel, the amount of rotation of the master wheel depending upon which of the keys is struck. If the operator manipulates the machine properly and does not attempt to strike a key when the master wheel is opposite to a pointing-off space in the totalizer the presence of the non rotatable members 17 or 17^b will not be felt, for the totalizer will move the non rotatable members past the master wheel without their producing an effect of any kind. But should the operator attempt to depress a figure key at a pointing-off point, that is, where the action of the type would be to print a figure in one of the pointing-off spaces, his attention will be immediately called to the fact for he will find that the key cannot be depressed, the master wheel being then in line with a non rotatable member 17. Thus he will be prevented both from registering the digit in the wrong column in the totalizer and in the case of a recording calculator from printing the digit in the wrong place on the recording sheet.

Although it is logical both from theoretical and structural considerations to select as the non rotatable member one which is directly engaged by the master wheel there is no essential reason why some other member in my form of totalizer may not be employed to act as a locking piece. To illustrate, by reference to Figs. 5 and 6 it is apparent that the receiving wheels 2 are always in mesh both with the carrying wheels 3 consequently the same locking effect on the master wheel would be obtained by inserting dummy figure wheels and locking them.

In the differential or digitizing mechanism here shown, toothed gear wheels are employed which are reversible, that is, operate positively in two directions in distinction to ratchet and similar gears which operate positively in only one direction. It will be understood that as far as my present invention is concerned it is not necessary that reversible gear wheels be employed. A ratchet differential mechanism operating positively in only one direction would be sufficient to prevent the depression of a key when the master wheel is held fast, and therefore I do not wish to be understood as limiting myself to reversible gearing as shown in the drawings.

What I claim as new and desire to secure by Letters Patent is:

1. A calculating machine having differential mechanism, a totalizer adapted to be engaged by the same to be driven thereby said totalizer having pointing-off intervals therein, and fixed members located in correspondence with said pointing-off intervals in the totalizer, said fixed members being adapted to be engaged by said differential mechanism for holding the same for the purpose described.

2. A calculating machine having differential mechanism the parts whereof are in positive gear connection so that if one part is held the others are in consequence also held; and 5 a totalizer adapted to be positively gear-connected to said differential mechanism to be operated thereby, said totalizer having fixed members at the pointing-off points for holding the differential mechanism from action 10 at such pointing-off points the differential mechanism and totalizer being relatively shiftable so that the differential mechanism will engage the totalizer in the different ordinal or columnar places thereof one after the 15 other.
3. In a calculating machine, a totalizer including tens carrying mechanism, receiving wheels for operating the same, and non rotatable members; said receiving wheels being 20 arranged in groups with one of said non rotatable members located between each group to correspond to the pointing-off point in the printed number; in combination with a master wheel, means for actuating it and 25 means for producing relative travel between the master wheel and totalizer whereby the master wheel may engage the receiving wheels and interposed non rotatable members successively.
4. In a calculating machine, a totalizer including tens carrying mechanism, receiving wheels for operating the same, and non rotatable members; said receiving wheels being 30 arranged in groups with one of said non rotatable members located between each group to correspond to the pointing off point in the printed number; in combination with a master wheel, means for actuating it and means 35 for producing relative travel between the master wheel and totalizer whereby the master wheel may engage the receiving wheels and interposed non rotatable members successively and means for moving the receiving 40 wheels and non rotatable members successively past the master wheel.
5. In a calculating machine, a totalizer including tens carrying mechanism, receiving wheels for operating the same, and non rotatable members; said receiving wheels being 45 arranged in groups with one of said non rotatable members located between each group to correspond to the pointing-off point in the printed number; in combination with a master wheel, figure keys, positive gear connections between said keys and said master wheel, whereby the holding of the master wheel prevents the depression of said keys, said master wheel, keys and intermediate connections constituting a differential mechanism; and means for producing relative 50 travel between the master wheel and totalizer whereby the master wheel may engage the receiving wheels and interposed non rotatable members successively.
6. In combination, a key operated typewriter having a stationary frame and a carriage traveling thereon; a non traveling master wheel; key operated differential mechanism for operating the same the parts of said differential mechanism being positively 55 geared together; a totalizer traveling in unison with said carriage, said totalizer including tens carrying mechanism and receiving wheels for operating the same, there being a receiving wheel for each of the actual ordinal 60 places in the totalizer but said receiving wheels being arranged in groups which are separated at the pointing-off points by a space equivalent to a letter or figure space in the printed sheet; and a non rotatable member located between each group of receiving wheels, the receiving wheels and non rotatable members being so located with reference to each other and to the master wheel that they are brought into operative line with the 65 master wheel successively the keys being therefore locked at the pointing-off points of the totalizer.

In witness whereof, I have hereunto subscribed my name in the presence of two witnesses.

HYMAN ELI GOLDBERG.
